UNITED STATES PATENT OFFICE.

JOHN L. NILSON AND JOHN PRINCE, OF CHICAGO, ILLINOIS.

WINDSHIELD-CLEANER PART.

Application filed August 19, 1922. Serial No. 582,837.

Our invention relates to windshield cleaners, and has particular reference to preservation of the efficiency and prolongation of life of the squeegee element. The object of 5 this invention is to obviate the loss of time, expense and wastage incidental to renewals of squeegees made necessary by weakenings and breakages of the flexible or rubber portion over the edges of its comparatively 10 rigid back or rib and the more rapid deterioration by sun and rain at that line of juncture between fiber and metal.

With the above named object in view our 15 invention consists in the novel construction, combination and arrangement of parts hereinafter described in detail, illustrated in the accompanying drawing, and more particularly pointed out in the appended claim.

In the drawing—

20 Figure 1 is a side elevation of a windshield cleaner arm carrying a squeegee and adapted to be secured to the windshield cleaner motor well known to this art, and showing a type of construction which forms the subject-matter of a separate application.

Figure 2 is a side view of Figure 1.

Figure 3 is a section taken substantially on the line 3—3 on Figure 2.

In the several views 2 represents the 30 cleaner-arm mounted in a bore of a shaft-coupling member 3 and therein secured by a set-screw 2'. The member 3 is shown with a split portion 4 extending from its side to a shaft-bore 5 adapted to be contracted upon the shaft (not shown) by a screw 4' adapted to contract the slit 4 and therewith the bore 5. On the opposite end of the arm 2 is a clamp comprising an open sleeve portion 6 that is contracted upon the 35 arm 2 and having sides 7 and 8 which are drawn by a screw 9 toward each other to grip the arm 2 and a U-shaped back or stiffening rib for the flexible portion of the squeegee held between said sides 6 and 7, but none of the foregoing parts are specifically involved in the present improvement.

The present improvement relates specifically to the construction of said U-shaped back or rubber holder and its edges—10 and 45 11—which have heretofore cut and acutely bent the flexible portion along the bending line. Said edges are in the present improve-

ment curved away from each other, as shown best in Figures 1 and 3, or receding away from immediate contact with the flexible portion, or rubber, 12 to leave normal spaces 13 and 14 between the flexible portion and its metallic holder, said spaces, as shown, contracting gradually inwardly. This gradual contact of metal with fiber, instead of the usual abrupt one, not only obviates acute bending of the fibrous portion along that line, but shades and protects against the elements that portion of the flexible part which is most severely bent during the oscillating movement of the squeegee over the surface of a windshield. The gradual closing in of metal upon the elastic portion 12 also tends during to and from bendings of the latter to work out any moisture tending to collect along the line of juncture in the old forms of construction, and always, as stated, obviates a suddenly weakened line which soon disrupts or weakens the required resistance to the elastic movements. 55 One of the movements is indicated by dotted lines in Figure 3 as well as the protection against cutting or abrupt bending afforded the flexible part 12 by the receding edges 10 and 11 which are arranged to lend support 60 in the usual way at the end of the bending movement without intensifying the bend along a single line, or intensifying the action of the elements along said line by sudden, unshaded contact of metal with fiber. The edges 10 and 11 form in themselves a rain and wind-shield, as it were, for that part of the fibrous portion which must endure the greatest bending strains, without at the same time causing the afore- 65 70 75 80 85 90 95 said injurious contacts.

We claim as our invention—

In a windshield cleaner squeegee, the combination with a flexible wiper strip, of a rigid channeled back between the sides of 95 which said strip is held and beyond which it projects, the edges of said sides adjacent to the bending line of said strip being arranged spaced apart and normally out of contact with said strip.

In testimony whereof we have hereunto signed our names.

JOHN L. NILSON.
JOHN PRINCE.
